UNITED STATES PATENT OFFICE

117,049

DESIGN FOR A PLASTIC SHEET OR SIMILAR ARTICLE

Harry E. Smith, Maplewood, N. J., assignor to Celluloid Corporation, a corporation of New Jersey

Application May 24, 1939, Serial No. 85,181

Term of patent 7 years

To all whom it may concern:

Be it known that I, Harry E. Smith, a citizen of the United States, residing at Maplewood, county of Essex, State of New Jersey, have invented a new, original, and ornamental Design for a Plastic Sheet or Similar Article, of which the following is a specification, reference being had to the accompanying drawing, forming part thereof.

In the accompanying drawing:

Fig. 1 is a plan view of a flat plastic sheet or similar article showing my new design;

Fig. 2 is a plan view of the plastic sheet of Fig.

1, bent into the form of a tube showing my new design.

The dominant feature of my design is the ornamentation appearing on the sheet consisting of striations of rippled pearl with recurrent variations of luster and color intensity and is independent of the thickness or configuration of the sheet.

I claim:

The ornamental design for a plastic sheet or similar article, substantially as shown and described.

HARRY E. SMITH.
